UNITED STATES PATENT OFFICE.

JULIUS HILBORN, OF NEW YORK, N. Y., ASSIGNOR TO MORITZ COHN, OF SAME PLACE.

DESIGN FOR A CORSET.

SPECIFICATION forming part of Design No. 13,441, dated November 21, 1882.

Application filed October 14, 1882. Term of patent 7 years.

To all whom it may concern:

Be it known that I, JULIUS HILBORN, of New York, in the county of New York and State of New York, have invented a new Design for Corsets; and I do hereby declare the following, when taken in connection with accompanying drawings and the letters of reference marked thereon, to be a full, clear, and exact description of the same, and which said drawings constitute part of this specification, and represent a side view.

This invention relates to a design for a corset with special reference to that portion commonly called the "hip-section"—that is to say, that part between the front and rear portions—and which lies directly below the arm and down over the hip; and the design consists in the ribbing or stayng of the section, as shown in the accompanying illustration and more fully hereinafter described.

A represents the rear portion of the front section, and B the front portion of the rear section. That part between these two constitutes the hip-section, and to which this design especially relates. At the front side is a vertical section, C, having the representation of a series of ribs extending from top to bottom and following the line of the seam between the hip

and front section, the series from the waist-line downward turned forward. The rear portion, D, of the hip-section is substantially plain. The intermediate portion has a band, E, at the top, with two series of transverse ribs, e. At the bottom is a similar band, F, also having two series, f, of transverse ribs. Between the bands E and F is the representation of a vertical series of ribs, G, extending from the one upper band to the other lower band, as shown in the accompanying illustration.

I claim—

The herein-described design for a corset, consisting in the hip-section representing a series of ribs on the front portion of said section extending from top to bottom, and the part D at the rear of the section with the representation of a band, E, at the top and F at the bottom, connecting the two parts C D, and ornamented by a series of transverse ribs, e and f, the central part between the parts C D and the bands E F ornamented by a series of vertical ribs extending from the upper to the lower band, as shown in the accompanying illustration.

JULIUS HILBORN.
